EDWARD CUNNIFF, OF NEW BEDFORD, MASSACHUSETTS, ASSIGNOR TO DRAPER COMPANY, OF HOPEDALE, MASSACHUSETTS, A CORPORATION OF MAINE.

THREAD-PARTING MECHANISM FOR LOOMS.

991,484.

Specification of Letters Patent.

Patented May 9, 1911.

Application filed December 1, 1910. Serial No. 595,062.

To all whom it may concern:

Be it known that I, EDWARD CUNNIFF, a citizen of the United States, and resident of New Bedford, county of Bristol, State of Massachusetts, have invented an Improvement in Thread-Parting Mechanism for Looms, of which the following description, in connection with the accompanying drawing, is a specification, like characters on the drawing representing like parts.

Automatic filling-replenishing looms of the "feeler" type are usually provided with means to cut the old filling between the cloth and the shuttle when filling replenishment is effected, the shuttle-feeler being relied upon to prevent replenishment if the shuttle is improperly boxed, mechanism of this character being shown in various patents, as for instance in United States Patent No. 683,423 granted to Draper September 24, 1901.

The thread parter is actuated by engagement with a suitable device carried by the lay, and it will be understood that if by chance the filling is cut when there is no operation of the replenishing mechanism there will be at least two empty picks in the cloth being woven, and while mechanism of the class above noted usually operates satisfactorily and properly there are times when in practice the filling is cut though there is no filling replenishment. To properly understand such faulty action it is necessary to briefly explain the sequence of operations which causes the same, it being understood that the thread parter is carried by the shuttle-feeler and that the movement thereof to operative position permits the positioning of the dog of the transferring mechanism in the path of the bunter on the lay. If the shuttle is properly boxed the shuttle-feeler completes its rearward movement and the dog is engaged by the bunter on the advancing lay, to effect filling replenishment in well known manner, while the thread parter is also operated to cut the old filling. On the other hand, if the improperly boxed shuttle is hit squarely by the shuttle-feeler not only is the thread parter prevented from acting upon the filling but the dog is depressed so that it strikes the inclined face of the bunter and slides downward thereover, and cannot operate the transferring device. When, however,

the shuttle is but slightly misplaced, leaving 55 its tapered end in the path of the feeler the latter will hit the exposed part of the shuttle and will be arrested sufficiently to depress the dog and prevent change of filling, but after so acting the feeler will often slide 60 off from or past the point of the shuttle, and the advancing lay is enabled to effect a partial operation of the thread parter, enough to grasp but not cut the old thread of filling. Thereafter, as the shuttle-feeler returns to 65 its normal position, drawing forward the filling, the setting pin on the movable parting blade will strike the setting cam in such manner that the blade will be completely closed, parting the filling, whereas 70 the true function of the setting cam is to open or set into operative position the blades of the thread parter. It will now be understood how the thread parting mechanism can at times part the filling when no fresh 75 filling supply has been inserted in the working shuttle.

My present invention, one practical embodiment of which is described herein, has for its principal object the production of a 80 thread parting mechanism of the general type before referred to but so constructed and arranged that the parting of the old filling cannot be effected unless replenishment of filling takes place, and a secondary 85 object of my invention is the production of means for obviating wear upon the bunter when the dog is depressed by or through the shuttle-feeler.

The various novel features of my invention will be fully described in the subjoined 90 specification and particularly pointed out in the following claims.

Figure 1 is a transverse section of a portion of an automatic filling-replenishing 95 loom with one embodiment of my invention applied thereto, the parts being shown in normal position; Fig. 2 is an enlarged detail in side elevation of a portion of the thread parting devices, to be referred to; Fig. 3 is 100 an enlarged detail, viewed from the right-hand side of the loom, of the dog in engagement with the bunter after initial depression of the said dog, to show the novel construction of the bunter and the operation 105 thereof; Fig. 4 is a detail in front elevation of the bunter shown in Fig. 3; Fig. 5 is a vertical section thereof on the line 5—5,

Fig. 4; Fig. 6 is a perspective view of the detachable bunter cap, removed from the bunter.

Referring to Fig. 1 the lay A^s , filling feeder F , transfeerer f' fulcrumed at f and having a downturned arm f^s on which is pivoted at f^s the notched dog m^s , and the controlling rock-shaft d' for the replenishing mechanism; the shuttle-feeler Y' , formed by the rearwardly-bent upper end of the arm Y , the latter mounted to rock on the stud a , the arm d^s fast on the rock-shaft d' and bearing on the pin 30 on said arm Y , and the spring S^s to normally maintain said arm and the parts carried thereby, and the dog m^s , in inoperative position, may be and are all substantially as in the Draper patent referred to.

Herein I have shown the finger n' , (which is fast on the arm Y) as provided with a cam slot n^s for the stud m^s on the dog, to control positively the position of the latter by or through the movement of the same arm, and also to enable depression of the dog to effect retractive movement of the shuttle-feeler, instead of using the cam-like or curved finger n' shown in the Draper patent, and which is well known to those skilled in the art.

The end of the shuttle-feeler is notched, as usual, to receive the old filling thread, and the parting device comprises essentially a fixed cutting blade c ; and a movable cutting blade c^s pivotally mounted at c^{2s} on the feeler and having a depending heel c' and a setting pin c^s , as in the Draper patent, and referring to Fig. 2 the setting cam c^s is arranged on the thread-catcher arm E , the cam coöperating with the pin c^s to open the blades when the shuttle-feeler Y' is swung rearward. The closing of the blades is effected by engagement of the heel c' with a blade-closing projection c^{2s} fixedly mounted on the lay, and if the closing operation is properly completed the pin c^s will slide over the top of the setting cam c^s and temporarily depress it as the shuttle-feeler returns to normal position.

The thread-catcher, denoted as a whole at C ; Figs. 1 and 2, forms no part of this invention and is fully shown and described in the Draper patent.

In accordance with my present invention the bunter for the transferring mechanism is made as a laterally extended and inclined part 1 of the upturned end of a bracket 2 in practice bolted to the lay, the front face 3 of the bunter being inclined downward and rearward and its upper face is beveled at 4, providing a V-shaped edge to coöperate with the usual notch m' in the end of the dog m^s when filling replenishment is to be effected. The bunter is cut away at its top to leave a clearance 5 between it and an L-shaped cap 6, shown separately in Fig. 6,

fixedly held in place on the bracket end and bunter by screws 7, 8, the overhanging part of the cap having a spring-seat or socket 9 therein.

The blade actuator c^{2s} can be made as a part of the bunter bracket 2, as shown in Fig. 1.

The bunter 1 has a rectangular opening 10 in which is mounted an impact member 11, notched at its lower end at 12, Fig. 5, to embrace the adjacent part of the bunter below the opening 10 and having at its upper end a lip 13 to engage the upper face of the bunter adjacent thereto. A spring 14 interposed between the cap 6 and said impact member normally maintains the latter seated, as shown in Figs. 3, 4 and 5, with a convex protuberance 16 thereon projecting beyond the bunter face 3, said protuberance being a short distance below the edge formed by the faces 3, 4 of the bunter. The spring 14 is seated in the socket 9 and in an opposite socket 17 in the impact member 11, so that the latter is yieldingly retained in normal position, but pressure upon the projecting part 16 will cause the impact member to be moved bodily rearward from the face 3 of the bunter into the clearance 5. This convex protuberance 16 is positioned opposite the path of movement of the notched end of the dog m^s when the latter is swung on its fulcrum f^s . When the dog is moved into position to be properly engaged by the upper, lateral edge of the bunter filling replenishment will be effected, as usual, and at such time the impact member 11 is inert and has no function to perform. If, however, the shuttle-feeler engages any part of the shuttle projecting from the mouth of the shuttle-box the forward movement of the lay acts through the shuttle-feeler and the finger n' to depress the dog m^s so that its notch m' cannot be entered by the upper edge of the bunter, and there will be no change of filling.

This condition of the parts is clearly shown in Fig. 3, the end of the dog above its notch abutting against the protuberance 16, and as the lay is still moving forward the convex face of said protuberance acts as a cam to accelerate the downward movement of said dog about the fulcrum f^s . That is, the cam action of the protuberance upon the dog is more rapid than would be the case if the depressing action were due only to the inclined face 3 of the bunter, and such accelerated motion of the dog acts through the finger n' to quickly retract the shuttle-feeler away from the still advancing lay. Such retraction moves the heel c' forward so that the actuator c^{2s} cannot engage it, hence no closing movement can be exerted upon the blade c^s , and there is no possibility of the old thread of filling being caught or grasped between the parting blades. Furthermore, the set-

ting pin c^6 cannot improperly strike or engage the setting cam c^8 when the shuttle-feeler finally returns to normal position, and consequently the blades c, c^8 will not be closed. Hence, even should the shuttle-feeler engage the shuttle very near its tip, the old filling cannot be parted unless the replenishing mechanism is operated, and any engagement of the feeler and shuttle sufficient to prevent filling replenishment will bring the dog temporarily under the control of the accelerator or protuberance 16, to operate as described. As soon as the accelerator has performed its stated function, which of course is instantaneous, the spring 14 yields as the lay completes its forward beat and permits the end of the dog to slide down the front of the bunter before the usual transference spring will yield, the spring 14 only having sufficient strength to temporarily hold the accelerator 16 in its operative position. The accelerator also takes up the wear due to the impact of the dog when filling replenishment is prevented, and thereby prevents the face of the bunter from becoming worn and hollowed out by frequent engagement with the dog.

It will be understood from the foregoing description that the initial result of engagement of the shuttle-feeler with the improperly boxed shuttle is to arrest and then push forward the shuttle-feeler, causing the finger n' to depress the dog from operative position and preventing filling replenishment, the dog coming into engagement with the accelerator. As the lay is still moving forward, the accelerator continues the depression of the dog but with increased speed, and the dog now acts through the finger n' to effect a further and rapid retraction of the shuttle-feeler. This latter retraction moves the heel c' forward too quickly for the actuator c^{20} on the lay to catch up with it before the setting pin c^6 has passed the critical point at or near the rear end of the yielding setting cam c^8 . As the parting blades cannot, therefore, be closed partly or completely it follows that the old filling thread cannot be caught between them, nor cut, when filling replenishment is prevented. In other words, if the improper positioning of the shuttle is detected by the shuttle-feeler, and the operation of the replenishing mechanism is thereby prevented, it is impossible to effect the operation of the thread parter.

Changes or modifications in details of construction and arrangement may be made by those skilled in the art without departing from the spirit and scope of my invention as set forth in the claims hereunto annexed.

Having fully described my invention, what I claim as new and desire to secure by Letters Patent is:

1. In a loom having filling replenishing mechanism and controlling means therefor,

including a bunter and a dog to coöperate therewith, a shuttle-feeler and a thread parter thereon to part the old filling, a lay, an actuator thereon for the thread parter, a controlling connection between the shuttle-feeler and dog and normally adapted to position the latter for coöperation with the bunter when filling replenishment is called for, engagement of the shuttle-feeler with the shuttle when improperly boxed acting through the controlling connection to move the dog from operative position, and means to continue such movement of the dog at accelerated speed, the accelerated movement of the dog acting through the controlling connection to retract the shuttle-feeler and thereby prevent operation of the thread parter by its actuator.

2. In a loom having filling replenishing mechanism and controlling means, therefore, including a bunter and a dog to coöperate therewith, a shuttle-feeler and a thread parter thereon to part the old filling, a lay, an actuator thereon for the thread parter, a controlling connection between the shuttle-feeler and dog and normally adapted to position the latter for coöperation with the bunter when filling replenishment is called for, engagement of the shuttle-feeler with the shuttle when improperly boxed acting through the controlling connection to move the dog from operative position, and a device on the bunter to engage and continue such movement of the dog at accelerated speed, the accelerated movement of the dog acting through the controlling connection to retract the shuttle-feeler and thereby prevent coöperation of the thread parter and its actuator.

3. In a loom having filling replenishing mechanism and controlling means therefor, including a bunter and a dog to coöperate therewith, a shuttle-feeler and a thread parter thereon to part the old filling, a lay, an actuator thereon for the thread parter, a controlling connection between the shuttle-feeler and dog and normally adapted to position the latter for coöperation with the bunter when filling replenishment is called for, engagement of the shuttle-feeler with the shuttle when improperly boxed acting through the controlling connection to move the dog from operative position, and a device yieldingly mounted on the bunter to temporarily engage and continue such movement of the dog at accelerated speed, to retract the shuttle-feeler and thereby prevent coöperation of the thread parter and its actuator, said device thereafter yielding to permit the disengagement of the dog therefrom.

4. An automatic filling replenishing loom in which the filling is replenished before complete exhaustion, having in combination, a thread parter for the old filling, a swinging

4

shuttle-feeler on which it is mounted, a lay, an actuator thereon for the thread parter, means, including a bunter on the lay and a dog to coöperate therewith, to effect the operation of the replenishing mechanism, a controlling connection between said shuttle-feeler and dog to operatively position the latter when filling replenishment is called for and the shuttle is properly boxed, engagement of said feeler with the shuttle if improperly boxed imparting an initial depression to said dog to prevent operative engagement thereof with the bunter, and means to temporarily engage the dog and 15 continue such depressive movement at accelerated speed, the latter movement of the dog acting through the controlling connection to impart a retractive movement to the shuttle-feeler and thereby prevent coöperation 20 of the thread parter and its actuator on the advancing lay.

5. An automatic filling replenishing loom, having, in combination, a shuttle-feeler movable automatically into filling position when 25 replenishment is called for, a thread parter mounted on the feeler and moved thereby into operative position when the shuttle is boxed properly, an actuator for the thread parter, mounted on the lay, means including 30 a dog, to effect the operation of the replenishing mechanism, a controlling connection between the shuttle-feeler and the dog to operatively position the latter if the shuttle is properly boxed, and to prevent such 35 positioning of the dog when the shuttle is improperly boxed when filling replenishment is called for, and separate means to coöperate with the dog when the shuttle is improperly boxed, and impart an additional 40 movement to the dog away from operative position, such movement acting through the controlling connection to positively retract the shuttle-feeler and thereby withhold the thread parter from coöperation with its 45 actuator.

6. In a loom, in combination, mechanism to replenish automatically the running shuttle with filling, means including a bunter on the lay and a dog, to effect the operation 50 of said mechanism, a shuttle-feeler to cause coöperation of the dog and bunter when the shuttle is properly boxed and to prevent such

coöperation when the shuttle is improperly boxed, a device carried by the feeler to part the spent filling at the replenishing side of the loom, an actuator for said device, carried by the lay, a positive controlling connection between the dog and the shuttle-feeler, and a cam-like device mounted on the bunter and adapted to temporarily engage and accelerate movement of the dog from operative position after initial movement of the dog by the shuttle-feeler upon engagement with the improperly positioned shuttle, such accelerated movement of the dog acting through the controlling connection to effect a quick retraction of the feeler and thread parting device thereon, to prevent coöperation of the latter with its actuator, the device on the bunter yielding to permit disengagement of the dog after the completion of its accelerated movement.

7. In a loom, having filling replenishing mechanism and controlling means therefor, including an apertured bunter on the lay and a dog to coöperate with said bunter, a shuttle-feeler and a thread parter thereon to part the old filling, an actuator for the thread parter, a controlling connection between the shuttle-feeler and dog, and normally adapted to position the latter for coöperation with the bunter when filling replenishment is called for, engagement of the shuttle-feeler with the shuttle when improperly boxed acting through the controlling connection to move the dog from operative position, an impact member yieldingly mounted in the aperture of the feeler, and having a cam-like protuberance normally projecting beyond the face of the bunter, said protuberance acting upon the dog after its movement from operative position by the shuttle-feeler, and temporarily continuing such movement at accelerated speed, to act upon the shuttle-feeler through the controlling connection, and thereby retract the thread parter from coöperation with its actuator.

In testimony whereof, I have signed my name to this specification, in the presence of two subscribing witnesses.
